UNITED STATES PATENT OFFICE.

JOSEPH W. ANTHONY, OF LYNN, MASSACHUSETTS.

LEATHER-FOLDING MACHINE.

1,326,827.

Specification of Letters Patent. Patented Dec. 30, 1919.

Application filed March 16, 1917. Serial No. 155,344.

To all whom it may concern:

Be it known that I, JOSEPH W. ANTHONY, a citizen of the United States, residing at Lynn, in the county of Essex and State of Massachusetts, have invented an Improvement in Leather-Folding Machines, of which the following is a specification.

This invention relates to an improvement in folding machines, wherein one or more edges of a piece of leather or similar material may be folded.

The particular structure involved in this invention is a machine for folding three edges of a folding case or receiver, the edges so folded being forced down upon an inner independent section.

The present machine is of the same general type as those described in my copending applications, Serial Nos. 79,205 filed February 18, 1916; 155,343, filed March 16, 1917, and 155,345, filed March 16, 1917, wherein the material to be folded is arranged upon a table supported for a limited reciprocating movement under pressure.

25 In the drawings:—

Figure 1 is a plan view of the improved machine.

Fig. 2 is a front elevation of the same.

Fig. 3 is a longitudinal section.

30 Fig. 4 is a plan of the bed illustrating particularly the arrangement of the wipers.

Fig. 5 is a bottom plan of the operating ring.

Fig. 6 is a sectional detail illustrating the means for depressing the bed.

Fig. 7 is a detail in elevation of the same.

Fig. 8 is a plan illustrating the forming plates and their connections.

Fig. 9 is a sectional view of the machine showing the positions of the parts following the initial operation.

Figs. 10, 11, 12, and 13 are sectional details showing successive operative stages of the folding operation.

45 Figs. 14 and 15 are perspective views, showing the movable sections of the side wipers and their operation.

Fig. 16 is a perspective detail showing a modified means for operating the forming plate carrier.

Figs. 17 and 18 represent respectively rear and face views of the specific article for which the machine is particularly designed.

50 Fig. 19 is a plan showing a slight modification with respect to the forming plates,

constructed with a view to forming round corners.

The present machine is specifically adapted for folding the edges, in this instance 60 three such edges, of a case involving an inner section 1 which may be constructed and arranged in any desired manner, and an outer or face section 2, the edges of which latter are folded down onto the inner section 65 to finish such edges. The outer surface of the completed article is also creased longitudinally of the folded edge by the present machine, for ornamental purposes. The specific product of the present machine is 70 illustrated in Figs. 17 and 18 of the drawings, and while particularly adapted for such product, it is, of course, obvious and readily apparent from the following description, that the machine is intended for 75 coöperation with any material in which a plurality of edges are designed to be simultaneously folded, the edge outline of the fold, governed in the present type of machine by the edge shape of forming plates, 80 being varied to the requirements of the particular line of fold desired.

The present machine has a base 10, above which is arranged for a limited movement to and from the base, a bed 11. Guide posts 85 12 rise from the base and pass through a lateral extension 13 projecting from a bracket 14 removably secured to the under side of the bed, and serve to guide the bed in movement. The lateral extension 13 is 90 spaced from the bed, and the under-surface of the bed is formed above the lateral extension with the recess 15 to receive an operating ring 16, mounted for limited rotary reciprocation in said recess and formed or 95 provided with means, whereby various necessary operations may be caused to follow in properly timed sequence.

The bed is formed about centrally with an opening 17, in which is arranged a table 100 18, forming one part of the clamping means for the material to be operated upon. The table is supported upon posts 19 passing through laterally extended plates 20 of brackets 21 secured to the base, the posts 19 105 having securing nuts or the like means 22, on their lower ends, and positioning springs 23 encircling the same above the plates 20 and between said plates and the table. The table is thus free to move downward against tension of the springs 23, the limit of movement being governed by the distance between the 110

nuts or securing heads of the rods and the base, the contact of said nuts, and base limiting the downward movement of the table and arranging it in effect as a fixed part of the base. The material is to be supported upon the table and said table has its upper surface preferably felted on an outline corresponding to that of the edges to be folded, but of a dimension less than that of the completed article to permit the edges of the article when completed to project beyond the edges of the table.

The upper surface of the table is preferably felted on the folding edge surface to provide a somewhat yielding surface for the action of the wipers, the use of the felted edge avoiding the necessity of positively limiting the downward movement of the table, and permitting the use of comparatively strong springs 23, which will provide necessary resistance in the completion of the fold.

The coöperating clamping member, which is adapted to overlie the material upon the table and clamp the same in working relation thereto, is carried by a clamp frame 24 of approximately rectangular shape having a laterally offset bracket 25, through which the clamp frame is connected for positive movement with the ring 16. The bracket 25 is formed with spaced vertically extending openings 26 in which are removably and adjustably secured operating rods 28 by set screws 27. The upper ends of the rods 28 are slidably mounted in a guide bracket 29, secured to and rising from the bed 11, the lower ends of said rods passing through the bed and being operatively connected to the ring 16 as will be later described. Mounted in the clamp frame 24 and for longitudinal movement therein is a resetting rod 30. A carrier 31 is adjustably secured upon the rod, by any fastening means, and includes an eye or bracket to receive the rod, and an underlying plate portion 32 which extends over the edge bars 33. Secured on the lower edges of the bars 33 are the forming plates 35, here shown as three such plates, though a single plate may be used if desired, and between the clamping plates 34 and edge bars are arranged the forming plates. The forming plates are adapted to be projected into an operative position beyond the edges of the clamping plates proper, so that the projecting portion of the forming plates may be utilized as an edge over which the material is to be folded, following which the forming plates are withdrawn or retracted from within the fold of material, to permit the wipers to force the fold down onto the underlying material. The forming plates are projected and retracted, and thus moved to operative or inoperative positions through movement of the resetting bar carrying with it the carrier 31.

The forming plates, which for purposes of particular folding operation designed by this machine present folding edges beyond three edges of the clamping plate, are formed of two sections 35, each comprising right angle portions 36, 37, the plates being arranged so that through their right angle formation, they coöperate with the side edges, and one end edge of the material. The right angle formation of the clamping plates forms the end edge folding portion which is thus made up of one section of each of the plates, and the meeting edges of these sections are so formed as to overlap in all positions, thereby maintaining an effective edge presentation through the forming plates in the full operative position of the latter. The plate 32 is formed adjacent its relatively inner edges with inclined slots 38, which slots receive pins 39 rising from the edge bars 33 of the carrier. It being desired to compel a relatively forward as well as an outward movement of the forming plates to properly positioning them, the forward movement is gained by forming in the plates additional inclined slots 40 which receive pins 41 depending from the edges of the clamping frame immediately overlying the forming plates, that is, the edges of such frame which support the clamping plate proper.

The longitudinal reciprocation of the resetting rod 30 will necessarily move the carrier and through movement of the latter project or retract the forming plates, and the forming plates are or may be held in one position or other through means to operate the carrier. The carrier is operated through movement of the resetting rod 30, by a resetting member 43, adapted to bear against one end of the rod 30, and secured upon a rod 44 slidably in a bracket 45 secured on the base, the rod being spring pressed in a direction to cause a roller carried on the end thereof to bear upon an operating cam 66 fixed upon a power shaft 67.

The carrier frame will be moved downwardly to cause the clamping plates 34 to engage the article previously deposited upon the table 18, and continue such movement to depress the table to a point below the bed surface to permit folding of the edge, the bed wipers mounted on the bed co-operating with each edge of the material to be folded. In the present instance there are three such wipers shown, an end wiper 47 and side wipers 48. The wipers are mounted for sliding movement in dovetailed recesses in the bed, and are so positioned normally that their inner or operative edges aline with the corresponding edges of the opening 17 in the bed. As the table with the article clamped thereon moves downwardly through the action of the descending clamping frame, the pro-

jecting edges of the material are carried past the edges of the wipers and of the bed, as will be plain from the Fig. 9 of the drawings. The wipers are then projected inwardly with relation to each other so as to turn the deflected portions of the material down onto the forming plates, which latter are in operative or projected relation. Immediately following this action of the wipers 5 the forming plates are withdrawn from the fold, and the downward pull or pressure upon the clamping frame relieved. The table with the article thereon is now held in its then depressed position by the wipers. The bed, as an entirety, is now depressed, causing the wipers to force the table downwardly through direct pressure upon the article. There is here a properly timed cycle of operations which as arranged 10 for in the present invention is carried out through the movement of a single member hereinbefore referred to as a cam ring. This cam ring 16 is of plate-like formation, having at intervals depending hollow block-like sections 51. The ring is guided in movement in the under surface of the bed beyond and concentric with the opening 17, and at an appropriate point between the block sections 51, the inner edge of the ring 15 has a depending wall 56, removably secured to the ring. This wall is formed with the cam slot 57 in which operates a roller 58, carried on a pin 59, projecting laterally from a cross bar 60, connecting the lower 20 ends of the clamp-frame operating rods 28. The cam slot 57, as shown in Fig. 9 is formed with an initial operating section 61 inclined downwardly, causing an initial depression of the carrier frame to move the 25 clamp plate and through the latter the table to the initial operating position previously described. When the parts have reached this position the wipers will have acted and the forming plates will be withdrawn from the folds of the material, and it is no longer necessary to maintain the clamping frame in clamping relation with the table, and hence, the final section 61 of the cam is of a height equal to the maximum vertical dimensions of the cam section 50 61, so that the carrier frame is wholly free from any cam influence, and may lift for an appreciable distance above the carrier though no specific means is deemed necessary herein to cause such movement of the frame. The upper surface of the cam ring proper is formed at appropriate points with cam slots 63, designed to operate the wipers through pins 49, depending from such wipers and entering the slots. The cam slots 63 for the wipers are substantially identical, each having an initial section 64, concentric with the movement of the cam ring and of the length to maintain the wipers 55 idle while an operative movement, or substantially a fully operative movement of the clamp frame is being had. The wiper cam slots are then inclined inwardly with respect to the cam ring presenting an operative section 65 so that as the pins 49 travel 70 in this operative section the wipers will be moved from a normal to a fully operative position. The wiper cam slots have a final holding section 66 concentric with the ring but on a plane inwardly of the idle section, the holding section maintaining the wipers in projected relation to complete the folding operation described and holding the folded section to insure its adherence to the material beneath. The depending sections 75 80 51 of the cam ring are positioned to co-operate with means carried by the upper ends of the guide posts 12 of the bed. Each of said depending sections 51 is formed in its inner wall with a cam slot 53 to receive 85 a roller 53' carried by a rod arranged laterally of the upper end of each of the posts 12, said posts being reduced at every upper end and the bottom walls of the depending sections 51 of the cam ring having guide 90 slots 51' concentric with the ring through which the reduced portions of the posts pass. The co-operation of the cam slots 53 with the rollers 53' serves to depress the bed to complete the folding operation, as 95 described, and as this is the final operation the said cam slots are formed with an initial idle section 54 in which travel of the rolls 53' may be had without moving the bed during the preceding operations, an inclined operative section 55 in which the travel of the rollers will depress the bed to complete the operation described, and a holding section 55', serving in the travel 100 of the rollers 53' therein to hold the bed 105 depressed to maintain the fold under the pressure of the wipers for a sufficient length of time to fix the cemented edges in folded relation.

The cam ring is given reciprocatory movement to that extent necessary to insure a full effect of the cam slots by a crank terminal 81 on the power shaft 67, the crank being connected by a pitman 82 to a pin 83 projecting radially from the cam 110 ring, the connections compensating for the differences in positions of the crank pin and cam ring pin throughout the respective movements.

The table previously described is limited 115 in its downward movement by contact of the guide rods with the base. This downward limit of the table is reached just prior to the final movement of the bed, under which conditions the table becomes a fixed support to insure an adequate pressure of the wipers upon the folds. It is at this final pressing movement that the creasing of the face side of the article is secured. This creasing is accomplished by a creasing 120

125 130

iron 79, supported on the base and having its upper creasing edge 80 in position to be engaged by the material just prior to the final depressed positions of the parts. The 5 iron is of course heated, preferably electrically or in any other desired way, so that a crease of the material is had during the final pressure.

The machine described is adapted to fold 10 three edges of the article that is both side edges and one end edge. The folded portions will naturally lap at the corners, and as it is desired that a smooth lap be secured it is considered important to avoid exactly 15 simultaneous folding of all edges. This result is obtained in the structure here shown by having the side wipers operate slightly in advance of the end wiper, as for example by having the idle portion 64 of 20 the end wiper cam slot slightly longer than the similar portions of the cam slots for the side wipers. In this operation of the parts provision must be made for avoiding interference between what would otherwise 25 be the meeting portions of the side wipers and end wipers. This result is provided for herein by providing the side wipers at the corners adjacent to the end wiper with separate sections 68, which are normally 30 adapted to complete the operative edge of the wiper, and which are connected to such wiper by a spring pressed plate 69 pivotally connected to a plate section 69', secured to the wiper section and to the upper surface 35 of the section 68. The end edge wiper is provided in line with the movable section of the side edge wiper with the plate 70 secured on the upper surface thereof, and having a finger 71 projecting slightly in 40 advance of the forward or operative edge of the wiper. This finger terminates in an upwardly and rearwardly inclined end 72, and the plate 69, for connecting the section 68 to the side edge wiper, has a cam 45 face 73 in the path of the end of the finger. The side edge wipers complete the wiping operation and as the end edge wiper advances to operative position the fingers 71 on the respective sides thereof will lift the 50 sections 68 of the side edge wipers to thus provide the necessary space for the full operative advance of the end edge wiper without interference.

It will be noted that the wipers and various operating parts of the machine are controlled and actuated through a cam ring, and that therefore it is entirely feasible to fold all four edges of the rectangular article as easily as the folding of the three 55 edges here illustrated, the fourth folding simply requiring an additional folding plate section and an additional wiper. It is also apparent that, if the edge to be folded necessitates round corners, round-corner 60 wipers may with ready facility be made to

coöperate with the construction described, and for convenience there is illustrated in Fig. 19 two round corner wipers 84 independently mounted and simultaneously and similarly operated by appropriate cam slots 70 in the cam ring.

The construction herein shown involves the operation of the forming plate carrier by an independent cam. However, it is apparent that, as shown in Fig. 16, the independent cam may be dispensed with and the resetting bar for the carrier operated by the cam ring 16. The bar 30, for this purpose, has a depending cam-roller 85 engaging an appropriately formed cam-slot 86 80 in the cam ring.

I claim:—

1. A folding machine comprising clamping means, forming plates associated therewith, means for operating the forming plates 85 to project them beyond the edge of the clamping means, wipers to coöperate with the material in the clamping means and fold the edge thereof about the projected forming plates and a rotary reciprocatory member 90 movable in one direction to operate the clamping means and the wipers.

2. A folding machine comprising clamping means, forming plates associated therewith, means for operating the forming plates 95 to project them beyond the edge of the clamping means, wipers to coöperate with the material in the clamping means and fold the edge thereof about the projected forming plates and a rotary reciprocatory member 100 movable in one direction to operate the clamping means and the wipers, and an independent cam for operating the forming plates.

3. A folding machine comprising material 105 clamping means, forming plates associated therewith, a movable bed, wipers carried by the bed, and a cam ring having cam control of the clamping means, wipers and bed.

4. A folding machine comprising material 110 clamping means, forming plates associated therewith, a movable bed, wipers carried by the bed, and a cam ring having cam control of the clamping means, wipers and bed, said cam ring operable to move said parts 115 into operative and inoperative positions.

5. A folding machine comprising a table, a clamping plate to coöperate with the table to provide a clamping means for the material, forming plates associated with the 120 clamping plate and connected therewith for operation outwardly and inwardly of the edge of the clamping plate, means for operating the forming plates, a bed surrounding but free of the table, the bed being 125 mounted for vertical movement, wipers movable in the plane of the bed to coöperate with the material and fold the edge thereof about the forming plates, and a cam ring mounted and movable in the bed and 130

- having cam grooves to time and control a movement of the clamping plate with respect to the table, a movement of the wipers with respect to the clamping means and a 5 movement of the bed.
6. A folding machine comprising a table, a clamping plate to coöperate with the table to provide a clamping means for the material, forming plates associated with the 10 clamping plate and connected therewith for operation outwardly and inwardly of the edge of the clamping plate, means for operating the forming plates, a bed surrounding but free of the table, the bed being 15 mounted for vertical movement, wipers movable in the plane of the bed to coöperate with the material and fold the edge thereof about the forming plates, a cam ring mounted and movable in the bed and having 20 cam grooves to time and control a movement of the clamping plate with respect to the table, a movement of the wipers with respect to the clamping means, and a movement of the bed and means for operating the 25 ring.
7. A folding machine comprising a table, a clamping plate to coöperate with the table to provide a clamping means for the material, forming plates associated with the 30 clamping plate and connected therewith for operation outwardly and inwardly of the edge of the clamping plate, means for operating the forming plates, a bed surrounding but free of the table, the bed being 35 mounted for vertical movement, wipers movable in the plane of the bed to coöperate with the material and fold the edge thereof about the forming plates, a cam ring mounted and movable in the bed and having 40 cam grooves to time and control movements of the clamping plate with respect to the table, movements of the wipers with respect to the clamping means and movements of the bed, means for operating the ring, 45 and means operated by the cam ring actuating means to control a movement of the forming plates.
8. A folding machine comprising a table, a clamping plate to coöperate with the table 50 to provide a clamping means for the material, forming plates associated with the clamping plate and connected therewith for operation outwardly and inwardly of the edge of the clamping plate, means for operating the forming plates, a bed surrounding but free of the table, the bed being 55 mounted for vertical movement, wipers movable in the plane of the bed to coöperate with the material and fold the edge thereof about the forming plates, a cam ring 60

mounted and movable in the bed and having cam grooves to time and control a movement of the clamping plate with respect to the table, a movement of the wipers with respect to the clamping means and a movement of the bed, in the order recited. 65

9. A folding machine comprising a table, a clamping plate to coöperate with the table to provide a clamping means for the material, forming plates associated with the 70 clamping plate and connected therewith for operation outwardly and inwardly of the edge of the clamping plate, means for operating the forming plates, a bed surrounding but free of the table, the bed being 75 mounted for vertical movement, wipers movable in the plane of the bed to coöperate with the material and fold the edge thereof about the forming plates, a cam ring mounted and movable in the bed and having 80 cam grooves to time and control movement of the clamping plate with respect to the table, movement of the wipers with respect to the clamping means and movement of the bed, and a creasing iron arranged below 85 the table and having its creasing edge slightly beyond the edge of the table and in position to be engaged by the material in the movement of the bed.

10. A folding machine including material 90 clamping means, fold defining means, edge folding means and an operating element for said means.

11. A folding machine including material clamping means, fold defining means, edge 95 folding means and an operating ring for said means.

12. A folding machine including material clamping means, fold defining means, edge folding means, and a cam ring controlling 100 the operation of said means.

13. A folding machine including material clamping means, fold defining means, edge folding means, and an oscillating cam ring controlling the operation of said means. 105

14. A folding machine including material clamping means, fold defining means, edge folding means, and a cam plate to control the operation of said means.

15. A folding machine including material 110 clamping means, edge folding means and oscillating means to control the operation of said means.

In testimony whereof, I have signed my name to this specification, in the presence of 115 two subscribing witnesses.

JOSEPH W. ANTHONY.
